UNITED STATES PATENT OFFICE

168,419

TABLE OR SIMILAR ARTICLE

William B. Petzold, Pittsfield, Mass., assignor to
General Electric Company, a corporation of
New York

Application December 15, 1951, Serial No. 17,749

Term of patent 14 years

(Cl. D33—14)

To all whom it may concern:

Be it known that I, William B. Petzold, a citizen of the United States, residing at Pittsfield, in the county of Berkshire, Commonwealth of Massachusetts, have invented a new, original, and ornamental Design for a Table or Similar Article, of which the following is a specification, reference being had to the accompanying drawing, forming a part thereof, in which

Fig. 1 is a perspective view of a table or similar article, embodying my new design;

Fig. 2 is a view similar to Fig. 1 with the drawers of the table in a partially extended position; and

Fig. 3 is a view similar to Fig. 2 with the drawers in a fully opened position.

I claim:

The ornamental design for a table or similar article, as shown.

WILLIAM B. PETZOLD.
